UNITED STATES PATENT OFFICE.

RICHARD IWANOWITSCH, OF PENZING, NEAR VIENNA, ASSIGNOR OF TWO-THIRDS TO CARL PEKLINGER, OF FLORIDSDORF, AND MAGDALENA KARDER, OF VIENNA, AUSTRIA-HUNGARY.

SAFETY-VALVE.

SPECIFICATION forming part of Letters Patent No. 427,264, dated May 6, 1890.

Application filed October 30, 1889. Serial No. 328,668. (No model.)

To all whom it may concern:

Be it known that I, RICHARD IWANOWITSCH, of Penzing, near the city of Vienna, Austria-Hungary, have invented certain new and useful Improvements in Safety-Valves, of which the following is a specification.

This invention relates to an improved safety-valve for steam-boilers, according to which the steam, which would issue from the valve 10 when the maximum pressure is exceeded, is not, as customary, allowed to escape into the open air, but is led through a branch pipe arranged at a suitable part of the valve into the combustion-chamber above the fire in such 15 manner that the fire will be damped according to the quantity of steam escaping through the safety-valve, thereby obviating the danger arising from increase of steam-pressure and reducing the said pressure to its normal 20 point.

In the accompanying drawing, my improved safety-valve is represented in vertical section.

The valve-cone *a* is weighted by the screw 25 *b*, a helical spring *d*, or other weight, according to the highest permissible steam-pressure. In order to protect the spring *d*, the same is provided with a movable packing, piston-ring, hemp ring, or the like, a Ramsbottom 30 piston *e* being represented by the accompanying drawing, and, as is evident, the nut *c* of the regulating-valve adjusts the tension of the helical spring *d* and is prevented from making any retrograde movement by means 35 of a lock-nut *c'*.

The valve-casing *f* is provided with a branch pipe *g*, arranged between the valve-cone *a* and the piston *e*, said branch pipe being connected to a tube *g'*, which is continued into the combustion-chamber and leads the steam from 40 excessive generation issuing through the safety-valve to the fire, whereby the latter is more or less damped, according to the quantity of steam passing the safety-valve, and in this 45 manner the pressure in the boiler is reduced to its normal point. A lever *i*, which has its fulcrum in lateral lugs *h*, permits the safety-valve to be lifted, but does not allow the said

valve to be overloaded, as the shorter arm *i'* reaches into the longitudinal slot *k* of the 50 valve-stem and comes in contact with the upper edge of the said slot. Before the arm can come in contact with the lower edge of the slot *k*, when the lever is raised, the said arm comes in contact with the lower edge *l* of 55 the slot *f'* in the valve-casing, or is prevented from coming in contact with the lower edge of the slot *k* in any other appropriate manner.

In order to prevent the safety-valve from being tampered with, a cap *m* is applied to the 60 upper part of the casing, and is attached thereto by means of a wire or its equivalent and a seal, such as *n*.

The above-described safety-valve with spring *d* can be employed for stationary boilers; but a direct weighting of the valve *a* can be employed, if desired, in which case, however, it is better to inclose the lever and the weights in a casing of wire-work, which can also be protected from being tampered with 70 by being sealed in any suitable manner.

Having now particularly described and ascertained the nature of my said invention and in what manner the same is to be performed, I declare that what I claim is—

In safety-valves of the kind hereinbefore set forth, a valve-casing *f*, having a valve-cone *a* located therein and connected to the piston-rod *e*, said cone *a* being weighted in accordance with the highest permissible pressure in the boiler by means of a spiral spring *d*, means, such as the cap *m*, for retaining the spring under pressure, and a screw, such as *b*, a regulating device comprising the nut *c*, lock-nut *c'*, and a two-armed lever *i i'*, pivoted in lateral lugs *h*, all in combination with a branch pipe such as *g*, and arranged to operate substantially as and for the purpose set forth in the foregoing specification, and shown in the accompanying drawing.

In witness whereof I hereunto set my hand in presence of two witnesses.

RICHARD IWANOWITSCH.
